UNITED STATES PATENT OFFICE

IRA V. GOODMAN, OF ALTOONA, PENNSYLVANIA

TOY TABLE

Application filed March 14, 1929. Serial No. 347,137.

This invention relates to new and useful improvements in toys, and particularly to toys which are mounted on tables.

One object of the invention is to provide a table of such construction that the scope of the toy may be enlarged or reduced, by the addition or removal of sections of the table.

Another object is to provide a toy of this character wherein the sections are provided with novel means for connecting them to each other, and for supporting them on the table.

Another object is to provide each section with supporting legs which are adapted to be folded over on one face of said section, for the purpose of producing compactness, and for protecting the devices mounted on the section.

Other objects and advantages will be apparent from the following description when taken in connection with the accompanying drawings.

In the drawings:

Figure 1 is a top plan view of a toy table made in accordance with the present invention.

Figure 2 is a side elevation of the same.

Figure 3 is a bottom plan view of the table.

Figure 4 is a vertical transverse sectional view on the line 4—4 of Figure 1.

Figure 5 is a fragmentary plan view showing the three legs, at the end of the table, engaged with the locking member 20.

Figure 6 is an enlarged detail sectional view on the line 6—6 of Figure 1.

Figure 7 is a bottom plan view of a modified form of the table.

Referring particularly to the accompanying drawings, 10 and 11 represent the semi-circular top boards of the end sections 12 and 13, of the table. Hinged to each side of each of the sections 12 and 13 is a supporting leg member 14, which includes the legs 15, the upper transverse connecting member, and the laterally extending flange 16, this latter portion being hinged to the table section, as clearly seen in the drawings. The center of the curved portion of each of the sections 12 and 13 is also provided with a leg member 17, of the same construction as

that just described. Secured to the upper face of each of said sections is a post 18, and mounted on the upper end of said post, by means of the vertical pivot 19, is a three-armed locking member 20. When the two side leg members are folded over their legs straddle the two diametrically opposite arms of the member 20, while the legs of the end leg member straddle the other arm of said member 20. The operator then rotates the member 20 into a position wherein said arms overlie the legs, whereby to hold the leg members in their folded positions. Disposed between the end sections 12 and 13 are the rectangular sections 21 each having a leg member 22 secured to each end, in a manner similar to that described in connection with the members 17, and carried by the upper face of each of these sections is a post 23, having a pivoted locking member 24, for holding the leg members of such sections, when folded, as hereinbefore described.

Pivotedly mounted on each end portion of one of the long sides of each section 21 is a hook 25, and in the other long edge of each section is an opening, each of said openings receiving the bill of a hook of an adjacent section, when said sections are placed with their edges together, as shown in the drawings. The straight edge portion of the section 13 is provided with similar hooks 26, which engage openings 27, in the adjacent edge of the section abutting therewith, while the straight edge of the section 12 has openings receiving hook 28 carried by the adjacent section 21, said openings being designated by the numeral 29. By this means all of the sections are held in proper position with relation to each other, while the leg members support the sections at the proper height from the floor. Mounted on the upper faces of the table sections are sections 30 of a railway system, the end sections 12 and 13 carrying the end curves 31 of the tracks. The system may be either mechanical or electric, as desired, and provision is made for the proper connection between the rail sections to carry the current. Other parts of the system, as the powerhouse 32, signals 33, a bridge 34, a tunnel 35, a station 36, and

other elements which will render the system realistic. The legs of the table will be of such length as to support the table at a height above the floor so that a child may 5 sit on the floor and reach the various parts of the system.

As shown in Figure 7, the modification comprises end sections 36', and connected to said sections, and extending therebetween, 10 are the slidably connected bars 37, on which the intermediate table top sections 38 are supported, each of such sections having on its upper face, portions of a toy railway system, similar to those shown in the other form 15 of the invention. By sliding the sections 36' toward and away from each other, room is provided for the desired number of sections 38.

What is claimed is:

- 20 1. A toy table including detachably connected sections each having a top, means for supporting each of said sections including leg members movably connected to the lower face of the individual section and foldable onto the upper face of said top, and means on the upper face of the top of each of said sections for holding said leg members of the section in folded position thereon.
- 25 2. A toy table including a plurality of detachably connected sections each having a top, legs hinged to the lower face of the top of each section and arranged to extend at right angles therefrom, at times, to support the section, and to be swung onto the upper face of said top, at times, posts on the upper face of the top of the section arranged to be straddled by said legs when so swung, and locking means on the posts for holding the legs in folded position.
- 30 3. A toy table including a plurality of detachably connected sections, legs movably connected to each of the sections and comprising L-shaped members each having a portion arranged to lie in contact with the lower face of the section in supporting relation thereto, said L-shaped members being adapted to be swung onto the upper face of the section, a post on said upper face, and a rotary locking member carried by the post for engagement with the legs.

In testimony whereof, I affix my signature.

IRA V. GOODMAN.
